UNITED STATES PATENT OFFICE.

EDWARD J. HENNELLY, OF JERSEY CITY, NEW JERSEY, ASSIGNOR TO IRVINGTON VARNISH & INSULATOR CO., A CORPORATION OF NEW JERSEY.

PAPER FEED FOR WINDING MACHINES.

Application filed May 10, 1927. Serial No. 190,160.

This invention relates to machines for winding strands of material, such as wire, thread, ribbon or filaments into coils, helices or bobbins and has particular reference to 5 machines for winding copper wire into coils or helices for use in various kinds of electrical apparatus. The particular embodiment of the invention herein described is in the nature of an improvement on the type of 10 machine disclosed, for example in U. S. Patent #1,368,536 granted February 15, 1921, to James C. Anderson and in U. S. Patent #1,521,372 granted December 30, 1924, to Bernard F. Johnson. In this type 15 of machine a plurality of coils are wound simultaneously in separated zones upon a spindle or mandrel, the convolutions of wire being wound in layers superposed one upon the other. The machine has provision for 20 introducing or injecting sheets of suitable material, such as paper, between the adjacent wire layers during the building up of the coils and while the spindle is in motion.

In machines of this type, the wires to each 25 of the separate coils are guided thereto by means of a reciprocating traverse bar which carries a plurality of spaced guides over which the wires pass before being wound upon the winding spindle. Driving means 30 are provided for reciprocating the traverse bar and changes its direction of travel to guide the wire to lay successive layers upon the winding spindle.

During the time interval occurring while 35 the traverse bar is reversing its direction at the end of each stroke a sheet or sheets of insulating material, usually paper, are inserted and wrapped around the last layer of a coil to form a new foundation for the succeeding layer and to further insulate the two layers.

The instant at which the sheet is inserted is of great importance and very critical. The sheet must be inserted immediately following 45 the last convolution of the layer of wire being wound and just prior to the first convolution of the new layer to be wound in order to prevent cross-overs of the convolutions of wire particularly cross-overs of two 50 successive layers of wire. The moment of proper insertion varies with the diameter of the wires which are being wound as does the angle of the wire relatively to the axis of the coil at which the wire will reverse its

direction and start a new layer, the latter 55 somewhat controlling the time of insertion of the paper.

The traverse bar is usually driven in its reciprocating movements by means of a screw shaft which is rotated alternately in reversed directions from a single driving shaft through a reversing clutch mechanism. This reversing clutch mechanism is controlled and reversed by a mechanism operated from the driving shaft and controlled by the traverse bar.

It has been customary to control the feeding means for inserting the sheets of insulating material from the same screw shaft which actuates the traverse bar in such a 70 manner that the feeding of the sheets of paper occurs the first partial revolution after the shaft has been reversed. It has been found, however, that the critical moment at which the insulating material should be 75 inserted could not be accurately controlled in this manner due to the lapse of time that is consumed by the operation of the reversing mechanism and, therefore, the insulating material could not always be inserted at the critical moment to prevent a cross-over of 80 the wire before or after a sheet was inserted.

It is the purpose of this invention to provide a mechanism to insert the insulating material at the critical moment and which 85 may be adjusted whereby cross-overs may be prevented regardless of the diameter of the wire being wound into coils.

In order to accomplish this desired result, the paper feeding means is controlled from 90 the driving shaft i. e. the source that drives the reversing mechanism, and the screw shaft rather than controlling the paper feeding means from the screw shaft after the reversing mechanism has functioned, whereby 95 the feeding of the paper is not a function of the reversing mechanism, following its action, but is independent thereof.

In machines of the type described, the reversing mechanism is under control of a 100 cam disk which is constantly urged to rotate by the driving shaft of the machine, but is only allowed to rotate intermittently through 180°. In accordance with this invention I attach to this cam a second cam which 105 controls the insertion of the insulating material in such a manner that the feeding of the paper takes place immediately upon move-

ment of this cam and is not delayed until after later movement of the reversing mechanism.

Other objects and advantages will be apparent from the following description of an embodiment of the invention and the novel features will be particularly pointed out hereinafter in claims.

In the accompanying drawings:

- 10 Fig. 1 is a plan view of a machine constructed in accordance with this invention; Fig. 2 is a section on line 2—2 of Fig. 1; Fig. 3 is a section on line 3—3 of Fig. 1; Fig. 4 is an enlarged plan view of the 15 paper controlling mechanism, and Fig. 5 is a detail in elevation of the controlling cam.

The type of winding machine illustrated in the drawing and to which the device of 20 this invention may be conveniently applied, is of the automatic type having a spindle shaft 1 rotatably supported between a head stock 2 and a tail stock 3 carried by a main frame 4. A pulley 5 is attached to the 25 spindle shaft which is driven by a belt 6 from any suitable source of power (not shown). A worm 7 on shaft 1 meshes with and drives a worm wheel 8 carried by a shaft 9, and shaft 9 carries a bevel gear 10 30 which meshes with and drives a pair of oppositely disposed bevel gears 11 and 12 forming part of a reverse clutch mechanism that is operated by a clutch lever 13.

The clutch lever 13 is pivoted at 14 intermediate of its ends, and has a resilient connection to a link 15 connected to a lever 16 and having a cam pin 17 running in a cam groove Figure 2 formed in a cam plate 18. The cam plate is mounted on and frictionally driven by the shaft 9. The cam groove of the plate 18 is adapted to reciprocate the link 15 in one direction during half the revolution of the cam plate, and in the opposite direction during the other half. The cam 45 plate is provided with peripherally disposed escapement teeth 19 which cooperate with an escapement pawl 20 carried by a slideable shaft 21. The shaft 21 when moved endwise will move the pawl 20 out of the path of 50 one of the escapement teeth 19 and into the path of the other since the teeth 19 are disposed substantially diametrically of the plate 18, and the cam plate 18 will be released for approximately half a revolution 55 for each endwise movement of the pawl 20 with the shaft 21. The shaft 21 is provided with rack teeth 22 which mesh with a small pinion 23 connected to and rotating a bell crank arm 24. The arm 24 is pivotally connected to a rod 25 which extends along the machine to approximately the opposite end where it is connected by a pivot 26 to a plate 27 slideable upon the frame 4 of the machine. The plate 27 is mounted upon the frame 4 60 for a limited endwise movement thereon.

Therefore, at each endwise movement of the plate 27, the direction of rotation of the shaft 30 to which bevel gears 11 and 12 may be alternately clutched by an operation of the lever 13, will be reversed. The shaft 30 70 is connected through a coupling 31 to a threaded or screw shaft 32 upon which a follower 33 is mounted by a screw-threaded connection so that the follower will move in one direction or the other along the shaft 32 75 depending upon the direction of rotation of the shaft.

A lever 34 is slideable in a sleeve 35 which is pivotally mounted at 36 upon the frame of the machine. One end of the lever 34 is 80 connected by a pivot 37 to the follower 33, so that as the follower moves along the shaft 32, the lever 34 will be rocked about the pivot 36.

A traverse bar 38 is mounted for sliding 85 reciprocatory movement in bearings 39 on the frame and is disposed parallel with and in close proximity to the winding spindle 1. This traverse bar 38 carries suitable wire guides 40 for directing the wires to a winding form mounted on and driven from the winding spindle 1. When the traverse rod moves endwise in its bearings, the guiding devices 40 will move endwise along the winding form and cause the wire to be 90 guided thereto to be laid upon the form in helical layers. A sleeve 42 is pivoted at 43 to one end of the traverse bar 38 and the lever 34 passes through the sleeve 42 so that when the lever 34 is rocked it will cause a 95 reciprocation of the traverse bar.

A threaded shaft 44, one end being left-hand threads, and the other half at the other end being right-hand threads, is rotatably mounted in the plate 27 and carries thereon a pair of spaced nuts 45 and 46 disposed one upon each portion of the shaft 44 and adapted to be engaged by the pivot pin 37 connecting the lever 34 to the follower 33 and which depends between the nuts 45 and 46 with the result that as the follower 33 moves along the shaft 32, the pin 37 will approach and then engage one of the nuts 45 or 46 and through it shift the plate 27 endwise and effect a reversal of rotation of the shaft 115 32 by the operation of the link 15 and its control of the reverse lever 13. The reversal in the movement of the follower 33 will cause corresponding reversals in the direction of travel of the traverse bar 38 and consequently reverses the direction of feeding of the wire to the winding forms thus starting new layers. It is obvious that the spacing of the nuts 45 and 46 determines the length of the layers of wire to be wound 120 upon the winding form.

Sheets of insulating material are supported by the usual spindles not herein shown, but shown and described in detail in the earlier patents referred to. The insulating 125

- material, preferably of paper, is led up through the machine to feeding, measuring, and cutting mechanisms, all as previously described in detail in the earlier patents, 5 and presented to a pair of feeding or accelerating rolls 50 mounted adjacent to and parallel with the spindle 1 and adapted to shoot the cut sheet of insulating material into the bight of the winding form and the 10 wire being wound thereon. The above mechanisms are all shown and described in the patents referred to and a further detail description of them is not deemed necessary herein.
- 15 The upper feed roll 50 extends beyond its end bearings 51 and has a universal connection 53 to a small shaft 54 which is rotatably carried upon an end member 55, adjustably secured to one end of a horizontal 20 arm 56^a of a lever 56, having a vertical arm 56^b and another horizontal arm 56^c all three intersecting at 56^d. The lever 56 is pivotally mounted at 57 at the lower end of arm 56^b upon a suitable bearing bracket 58 carried by frame 4. A roller 59 is fixed to the other end of the small shaft 54 for rotation therewith, and is adapted to be carried into frictional driving engagement with an annular groove 60 cut into the periphery of the 30 driving pulley 5 when the lever 56 is rotated in one direction, that is, forwardly upon its pivot 57.
- To the outer extremity of the other horizontal arm 56^c then is adjustably attached the 35 bifurcated member 61 which carries a cam roller 62 rotatably mounted between its bifurcated ends. Cam roller 62 engages a cam disc 63 integral with or attached to cam plate 18. Cam disc 63 has two substantially diametrically opposite cut-away portions 64 40 bounded by an inclined portion 65 upon one end and by the abrupt shoulder 66 formed by the end of a wear plate 67 adjustably secured to the inner wall of the cut-away portion at the other end thereof. A spring 68 normally 45 urges the lever 56 in its forward position.
- It follows therefore that when the traverse bar reaches the end of its stroke pawl 20 will be moved out of the path of one of the 50 escapement teeth 19 and thus allow cam plate 18 to revolve 180° or half revolution to shift the reversing mechanism to reverse the direction of rotation of shaft 32 to cause the traverse bar to change its direction of motion and lay a new layer of wire.
- 55 At the instant cam plate 18 starts to rotate or as soon thereafter as may be desired cam roller 62, which is normally up upon the wear plate 67 secured to the cam disc 63, will drop to the inner wall of the cut-away portion 64 and allow lever 56 to swing upon its pivot 57 and permit roller 59 to engage in groove 60 of the pulley 5. Roller 59 through shaft 54 and connection 53 will rotate feed 60 accelerating rolls 50 and shoot a sheet of insulating material into the bight of the rotating coil and wire. As cam disc 63 continues in its rotation cam roller 62 will follow up the inclined end 65 and around to the wear plate diametrically opposite the previous one where the cam plate and cam disk will come to a rest due to engagement of the pawl 20 and the alternate escapement tooth 19.
- 65 It can readily be seen that by the described mechanism the accelerating roller 50 will be rotated for a short period for every half revolution of the cam plate 18 and cam disc 63 and that the rotation will take place immediately upon the completion of a stroke of the traverse bar without the necessity of waiting for complete action of the reversing mechanism. The exact timing of the feeding of the paper may be accurately regulated by adjustment of either or both of the two adjustable end members upon the two arms 56^a and 56^c of lever 56 and also by adjustment of the wear pieces 67 secured to the cam disc.
- 70 Various changes may be made in the details of construction without departing from the spirit and scope of the invention as defined in the appended claims.
- 75 Claims:
1. In a winding machine, a winding spindle, a traverse member for guiding a wire to said spindle, a shaft for reciprocating said traverse member to cause it to lay successive layers of wire on said spindle, rollers adjacent said spindle for feeding a sheet of insulating material to said spindle, a driving shaft for rotating said first mentioned shaft and means actuated directly from said driving shaft for intermittently operating said feed rolls.
- 80 90
2. In a winding machine, a winding spindle, a traverse member for guiding a wire to said spindle, a shaft for reciprocating said traverse member to cause it to lay successive layers of wire upon said spindle, rollers adjacent said spindle for feeding a sheet of insulating material to said spindle, a driving shaft for rotating said first mentioned shaft, a cam on said driving shaft and means operated by said cam for intermittently rotating 100 said feed rolls.
- 105 110
3. In a winding machine, a frame, a winding spindle mounted for rotation therein, a traverse member for guiding a wire to said spindle, a shaft for reciprocating said member to cause it to lay successive layers of wire on said spindle, a driving shaft for rotating said first mentioned shaft, reversing mechanism interposed between said driving shaft and said other shaft, rollers adjacent 115 said spindle for feeding a sheet of material to said spindle, and means connected to said driving shaft for intermittently operating said feeding rollers.
- 120 125
4. In a winding machine, a frame, a wind-

- ing spindle mounted for rotation therein, a traverse member for guiding a wire to said spindle, a shaft for reciprocating said member to cause it to lay successive layers of wire on said spindle, a driving shaft for rotating said first mentioned shaft, reversing mechanism interposed between said driving shaft and said other shaft, rollers adjacent said spindle for feeding a sheet of material to said spindle, and means on said driving shaft for actuating said reversing mechanism and for intermittently operating said feeding rollers.
5. In a winding machine, a frame, a winding spindle mounted for rotation therein, a traverse member for guiding a wire to said spindle, a shaft for reciprocating said member to cause it to lay successive layers of wire upon said spindle, a driving shaft for rotating said first mentioned shaft, reversing mechanism interposed between said driving shaft and said other shaft, rollers adjacent said spindle for feeding a sheet of material to said spindle, a bracket pivoted to said frame, means for driving said rollers carried by said bracket, and means on said driving shaft including a cam attached thereto and associated mechanism for operating the reversing mechanism and a second cam attached to said first mentioned cam for engaging said bracket to intermittently operate said feeding rollers.
6. In a winding machine, a frame, a winding spindle mounted for rotation therein, a traverse member for guiding a wire to said spindle, a shaft for reciprocating said member to cause it to lay successive layers of wire upon said spindle, a driving shaft for rotating said first mentioned shaft, reversing mechanism interposed between said driving shaft and said other shaft, rollers adjacent said spindle for feeding a sheet of material to said spindle, a bracket pivoted to said frame, means for driving said rollers carried by said bracket, and means on said driving shaft for engaging said bracket to intermittently operate said feeding rollers.

In witness whereof, I hereunto subscribe my signature.

EDWARD J. HENNELLY.
